FOLLOWER FOR FILING CABINETS

Original Filed Nov. 12, 1938

A technical line drawing of a window frame assembly. The frame is shown in an open state, revealing the internal structure. Several components are labeled with numbers:

- 8: A vertical strip of material, possibly a gasket or reinforcement, attached to the top edge of the frame.
- 5: A diagonal strip of material, possibly a gasket, attached to the top-left corner of the frame.
- 11: A horizontal strip of material, possibly a gasket, attached to the top edge of the frame.
- 10: A vertical strip of material, possibly a gasket, attached to the bottom edge of the frame.
- 2: A horizontal strip of material, possibly a gasket, attached to the right edge of the frame.
- 3: A horizontal strip of material, possibly a gasket, attached to the right edge of the frame.
- 9: A vertical strip of material, possibly a gasket, attached to the bottom-left corner of the frame.
- 6: A vertical strip of material, possibly a gasket, attached to the bottom edge of the frame.
- 7: A small, unlabeled vertical strip of material, located between the 9 and 6 labels.
- 1: A small, unlabeled horizontal strip of material, located near the bottom center of the frame.
- II: A label with a leader line pointing to the top-left corner of the frame.
- 12: A label with a leader line pointing to the top-right corner of the frame.
- 13: A label with a leader line pointing to the bottom-right corner of the frame.

The drawing uses fine lines and cross-hatching to indicate the thickness and texture of the various components.

FOLLOWER FOR FILING CABINETS

Arthur C. Strayer, Beaver, Pa.

Original application November 12, 1938, Serial No. 240,136. Divided and this application January 26, 1939, Serial No. 253,007

3 Claims. (Cl. 129—31)

This invention relates to a follower for a filing cabinet, and it is an object of the invention to provide a follower or support for application within a drawer comprised in the cabinet and wherein the support or follower when in applied position requires but little space.

It is also an object of the invention to provide a follower or support for application within a drawer of a filing cabinet and wherein the follower or support and the side walls of the drawer are so constructed and arranged to provide means whereby the follower or support may be readily applied or removed and when in applied position may be readily shifted within the drawer as required.

The invention consists in the details of construction and in combination and arrangement of the several parts of my improved follower for a filing cabinet whereby certain important advantages are attained and the device rendered simpler, less expensive and otherwise more convenient and advantageous for use, as will be herein after more fully set forth.

The novel features of my invention will hereinafter be definitely claimed.

In order that my invention may be the better understood, I will now proceed to describe the same with reference to the accompanying drawing, wherein:

30 Figure 1 is a vertical sectional view taken thru a filing cabinet having applied thereto a support or follower constructed in accordance with an embodiment of my invention;

Figure 2 is a detailed sectional view taken substantially on the line 2—2 of Figure 1 with the casing omitted;

Figure 3 is a view partly in section and partly in elevation showing the support or follower in an intermediate position when either applying or removing the same;

Figure 4 is a view similar to Figure 3 but showing the follower in its first position when being applied or in its final position when being removed.

45 As disclosed in the accompanying drawing, C denotes a casing with which is associated a sliding drawer D, said casing C and drawer D being of a type as particularly described and claimed in my pending application Serial No. 240,136 filed November 12, 1938, of which the present application is a division.

The drawer D includes a bottom wall 1 and the side walls 2. The upper marginal portions of the side walls 2 are returned to provide the 55 internal depending flanges 3. These flanges 3

are spaced from the adjacent portions of the side walls 2 whereby is provided downwardly facing trackways 4 for the support or follower S.

As herein comprised the support or follower S embodies a body plate 5 of a width to fit substantially snug transversely within the drawer D. The marginal portions of this body plate 5 are defined by the rearwardly directed bottom flange 6, side flanges 7 and top flange 8, said flange 8 being preferably of a reverted type. These flanges 6, 7 and 8 assure the support or follower S having requisite strength and rigidity while the side flanges 7 provide means for the proper securing of the retaining plates 9. The plates 9 are each of a height substantially equal to the height of 15 a side wall 2 and of a length less than the distance between the bottom wall 1 of the drawer D and the lower marginal portions of the flanges 3. Diagonally opposed corner portions of each of the plates 9 are rounded, as at 10. These rounded 20 edges 10 are outwardly disposed and each is preferably described on an arc of about the approximate axial center of the plate 9.

The plate 5 is secured between the plates 9 on a predetermined rearward angle with respect to 25 the longitudinal axes of the plate 9 so that when the support or follower S is in applied or working position within the drawer D, the plate 5 will be disposed on an upward and rearward incline to facilitate transfer of records or facilitate access 30 to the records within the drawer D in advance of the follower or support S.

In applying the support or follower S it is first placed within the drawer D with the plate 5 forwardly directed and the longitudinal axes of the 35 plates 9 at right angles to the bottom wall of the drawer D as illustrated in Figure 4. In this position the plates 9 will be positioned entirely below the flanges 3 and upon swinging the plate 5 upwardly as indicated in Figure 3, the lower 40 rounded corners of the plates 9 will rock upon the bottom wall 1 of the drawer and the upper marginal portions of the plate 9 enter the trackways 4 until the plate 5 assumes its full or effective working position as illustrated in Figure 1. 45 In removing the support or follower S the reverse operation is employed.

The plates 9 may be secured to the side flanges 1 of the plate 5 in any desired manner but preferably by spot welding, as indicated at 11. The 50 plate 5 is of a size to extend a desired distance above the side walls 2 when the support or follower is in working position and this support or follower S may be slid into any desired position along the drawer D.

In shifting the support or follower S it is preferred that the plate 5 be substantially vertically disposed or arranged at right angles to the bottom wall 1 of the drawer D as illustrated in Figure 3. When the plate 5 is in its rearward slanting position as illustrated in Figure 1, it is effectively locked in such position under the cam action against the upper portion of the plate 5 by the papers or the like placed within the drawer for filing.

To facilitate the entrance of the upper portion of each of the plates 9 within its trackway 4, said upper portion of the plate 9 is outwardly offset, as at 12, (see Figure 2). It is also to be stated that the upper offset portion 12 of each of the plates 9 is free from the plate 5 or more particularly the adjacent flange 7 thereof. This separation of the upper portions of the plates 9 allows for expansion as when the drawer D is overloaded the side walls 2 have a tendency to expand. However, when the support or follower, as herein disclosed, is under such expansion the plates 9 will sway out with the side walls 2 without disengaging from the trackways 4.

It is to be particularly pointed out that the support or follower S as comprised herein is one which is not a permanent part of the drawer D; requires but little space when in applied position; readily slides into any position desired along the drawer; and readily locks itself in any desired selective position.

From the foregoing description it is thought to be obvious that a follower for a filing cabinet constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with a drawer having side walls provided along their upper portions with downwardly facing trackways, a follower for said drawer comprising a plate to fit transversely within the drawer, side plates secured to the

lower portion of the first plate, said side plates each being of a length less than the distance between the bottom of the drawer and the trackways and of a height substantially equal to the height of the side walls of the drawer, diagonally opposed corners of the side plates being rounded, said side plates being free of the trackways when the follower is within the drawer and the first named plate disposed lengthwise of the drawer, the upper marginal portions of the side plates engaging within the trackways when the first named plate is swung upwardly.

2. In combination with a drawer having side walls provided along their upper portions with downwardly facing trackways, a follower for said drawer comprising a plate to fit transversely within the drawer, side plates secured to the lower portion of the first plate, said side plates each being of a length less than the distance between the bottom of the drawer and the trackways and of a height substantially equal to the height of the side walls of the drawer, diagonally opposed corners of the side plates being rounded, said side plates being free of the trackways when the follower is within the drawer and the first named plate disposed lengthwise of the drawer, the upper marginal portions of the side plates engaging within the trackways when the first named plate is swung upwardly, the rounded corners of the side plates being described about 30 substantially the axial centers of the side plates.

3. In combination with a drawer having side walls provided along their upper portions with downwardly facing trackways, a follower for said drawer comprising a plate to fit transversely within the drawer, side plates secured to the lower portion of the first plate, said side plates each being of a length less than the distance between the bottom of the drawer and the trackways and of a height substantially equal to the height of the side walls of the drawer, diagonally opposed corners of the side plates being rounded, said side plates being free of the trackways when the follower is within the drawer and the first named plate disposed lengthwise of the drawer, the upper marginal portions of the side plates engaging within the trackways when the first named plate is swung upwardly, the upper portions of the side plates being free of connection with the first named plate.

ARTHUR C. STRAYER.
